UNITED STATES PATENT OFFICE.

JAMES JOHNSON, OF EAST HAMPSTEAD, NEW HAMPSHIRE.

PLOW-COLTER.

SPECIFICATION forming part of Letters Patent No. 299,396, dated May 27, 1884.

Application filed April 23, 1883. (No model.)

To all whom it may concern:

Be it known that I, JAMES JOHNSON, a citizen of the United States, residing at East Hampstead, in the county of Rockingham and State of New Hampshire, have invented a new and useful Improvement in a Combined Colter and Reversible Mold-Board, of which the following is a specification.

The object of my invention is to so arrange 10 the colter as to cause its lower edge to bear against the landside of the plow-point at every reversion of the mold-board in a reversible or side-hill plow.

In plow-colters as ordinarily applied a 15 space is left between the point and lower edge of the colter and the point of the plow sufficient to allow of the passage of roots and other obstructions which clog the plow, and necessitate the stopping of the work to remove the 20 obstructions, and oftentimes causing the breaking of the beam at the center-bolt connection.

The invention consists in beveling the lower 25 end of the colter to an edge and arranging the front edge of the same so as to bring it as near as practicable on a line with the land side of the mold-board, thus causing the opposite side of the plow-point to be presented to an opposite side of the colter-point at every reversion of the mold-board.

Referring to the accompanying drawings, 30 Figure 1 represents a plow containing my improvement. Fig. 2 represents the colter enlarged. Fig. 3 represents the brace, and Fig. 4 is a section of the colter on the line xx of Fig. 2.

A is the plow-beam. B is a reversible mold-board, of any ordinary construction, and C the plow-point. These parts, being well known, require no further description.

D is the colter, which passes through and is 40 bolted to the beam A, as shown. The upper

edge, d, and lower ends, e, of the lower portion of the colter are made considerably sharp, as shown. The lower beveled end, e, of the colter is placed in contact with the upper side of 45 plow-point C, and extends down a short distance—say about three-quarters of an inch—so as to prevent roots or other obstructions from passing between the two parts. The colter is brought to its proper relation to the land-side 50 at every reversion of the mold-board or plow. By means of my improvement I am enabled to dispense with the use of levers, gears, or other device for setting the colter, as heretofore used, and cause the plow-point to be 55 brought in proper relation to the colter at every reversion of the mold-board without changing the position of the colter.

E is a brace bolted to the colter D, as shown, and attached at its other end to the 60 under part of the front portion of the beam A, by means of which the colter is relieved from the strain to which it would otherwise be subjected in coming in contact with roots and other obstructions.

What I claim as my invention is—
The colter D, having a sharp edge, d, on the 65 upper part of the lower portion, and a sharpened end, e, in combination with the beam A and brace E, and the reversible plow-point C 70 and reversible mold-board B, whereby the lower end of the colter is made to bear against the land side of the plow-point at every reversion of the mold-board, as set forth.

In testimony whereof I have signed my name 75 to this specification in the presence of two subscribing witnesses.

JAMES JOHNSON.
